CABINET FOR TOILET ARTICLES

Herbert H. Ryan, 601 Columbia Drive, Bayshore
Gardens, Bradenton, Fla.

Filed June 18, 1962, Ser. No. 70,608

Term of patent 3½ years

(Cl. D4—3)

FIG. 1 is a front perspective view of a cabinet for toilet articles, showing my new design.

FIG. 2 is a front elevational view thereof shown in open position.

FIG. 3 is a vertical cross-sectional view thereof taken on the line 3—3 of FIG. 1.

FIG. 4 is a fragmentary view showing the upper left hand corner thereof.

The side not shown is substantially like the side shown.

I claim:

The ornamental design for a cabinet for toilet articles, as shown and described.
